(57) **CLAIM**

The ornamental design for a scooter footbelt, as shown and described.

DESCRIPTION

FIG. 1 is a rear perspective view of a scooter footbelt, showing my new design;

FIG. 2 is a top view thereof;

FIG. 3 is a bottom view thereof;

FIG. 4 is a rear view thereof;

FIG. 5 is a front view thereof;

FIG. 6 is a right side view thereof;

FIG. 7 is a left side view thereof; and,

FIG. 8 is a perspective view showing the scooter footbelt in the environment in which it is to be used.

The scooter shown in broken lines in FIG. 8 forms no part of the claimed design.
